GAME BOARD

Merle L. Cables, P.O. Box 246, Cutten, Calif.

Filed Aug. 26, 1964, Ser. No. 31,440

Term of patent 3½ years

(Cl. D34—5)

FIG. I

FIG. 2

FIG. 1 is a plan view of my game board showing my new design; and

FIG. 2 is a fragmentary enlarged perspective of a portion of the board which is of conventional thickness illustrating one of the spinners, of which all others are alike.

The dominant features of my design reside in the portions shown in full lines.

I claim:

The ornamental design for a game board, as shown and described.
